Primary Examiner — Carol Rademaker*(74) Attorney, Agent, or Firm* — Judy W. Chung(57) **CLAIM**

The ornamental design for a bottle, as shown and described.

DESCRIPTION

FIG. 1 is a top, front, and right side perspective view of a bottle according to the new design;

FIG. 2 is a top, front, and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the drawing views of the pour spout and threads, a portion of the left sidewall, and the bottom surface of the bottle are included for the purpose of showing environmental structure that forms no part of the claimed design.
